N. S. Wedder, of Troy, N. Y.
Letters Patent No 1202, dated Feb. 14. 1860.

The schedule referred to in these ^{mm} Letters Patent and making part of the same.

To all whom it may concern:

Be it known that I, N. S. Wedder, of the City of Troy, in the County of Rensselaer, and State of New York, have invented or produced a new and original design for plates of a Parlor Stove; and I do hereby declare that the following is a full and exact description of the same, reference being had, by letters, to the annexed photographic drawing which makes a part of this Specification.

Arrange the ornaments marked, a, along the top, and the open-work panels, d, d, d', d', and flat-work ornaments, e, e, e', e', along the sides of the front, or side-plate or plates, of the stove; and dispose the ornament, b, on the upper doors or panels, F, F, and place the ornament, c, upon the lower doors or panels, G, G, of the stove, as represented in the annexed photographic drawing.

What I claim as my invention or production and desire to secure by Letters Patent, is the ornamental design of the stove-plate or plates herein specified and represented in the annexed photographic drawing.

Witnesses,

Thos J. Cornelius. {
